UNITED STATES PATENT OFFICE

112,878

DESIGN FOR A FLAGPOLE

Gunnar C. Froelich, Philadelphia, Pa.

Application October 27, 1938, Serial No. 80,709

Term of patent 7 years

To all whom it may concern:

Be it known that I, Gunnar C. Froelich, a citizen of Denmark and a resident of Philadelphia, in the county of Philadelphia and State of Pennsylvania, have invented a new, original, and ornamental Design for Flagpole, of which the following is a specification, reference being had to accompanying drawing, forming part thereof.

The figure is a side view of a flagpole, showing my new design.

I claim:

The ornamental design for a flagpole, as shown.

GUNNAR C. FROELICH.
